[57] **CLAIM**

The ornamental design for a lap-top computer, as shown and described.

DESCRIPTION

FIG. 1 is a perspective view of a lap top computer showing my new design in the opened condition;

FIG. 2 is a perspective view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a left side elevational view thereof; and

FIG. 8 is a right side elevational view thereof.

The computer is shown in the closed condition in FIGS. 2-8.
